UNITED STATES PATENT OFFICE

162,002

DENTAL HANDPIECE

Ray W. Brown, Denver, Colo., assignor to Densco,
Incorporated, Denver, Colo., a corporation of Colorado

Application June 6, 1949, Serial No. 3,080

Term of patent 7 years

(Cl. D24—1)

To all whom it may concern:

Be it known that I, Ray W. Brown, a citizen of the United States of America, residing at the city and county of Denver, State of Colorado, have invented a new, original, and ornamental Design for a Dental Handpiece, of which the following is a specification, reference being had to the accompanying drawing, forming part thereof.

Figure 1 is a side elevation of a dental handpiece showing my new design. Figure 2 is a front end elevation of the showing of Figure 1. Figure 3 is a side elevation of the handpiece shown in Figure 1 with the elements of the organization in an alternative operating relation. Figure 4 is a top plan view of the showing of Figure 1.

The dominant features of my design reside in the portions shown in full lines.

I claim:

The ornamental design for a dental handpiece, substantially as shown and described.

RAY W. BROWN.
